UNITED STATES PATENT OFFICE.

RUSSELL C. BLAKESLEE, OF TORRINGTON, CONNECTICUT.

DESIGN FOR A BOBBIN-HOLDER AND THREAD-CATCHER.

SPECIFICATION forming part of Design No. 29,965, dated January 10, 1899.

Application filed December 14, 1898. Serial No. 699,271. Term of patent 7 years.

To all whom it may concern:

Be it known that I, RUSSELL C. BLAKESLEE, a citizen of the United States, residing at Torrington, in the county of Litchfield and 5 State of Connecticut, having invented and produced a new and original Design for a Bobbin-Holder and Thread-Catcher, of which the following is a specification.

My present invention relates to a new and 10 original design for a bobbin-holder and thread-catcher, the design being illustrated in the accompanying drawings, wherein—

Figure 1 is a top perspective view of the device; Fig. 2, a top plan view, and Fig. 3 a 15 perspective view seen from the bottom.

The holder consists of the annular plate A, from the periphery of which arise the arms B, the major portion a of the arms being curved outwardly, as shown, while near the 20 upper end there is formed an inwardly-projecting section b.

Extending upwardly from the face of the plate A are a series of pins or studs C, while extending down from the central opening of said plate is a tube or cylindrical piece D. 25 Said tube carries at its lower end a cup-shaped piece E, Figs. 1 and 3, which extends up around the tube at a slight distance therefrom. Immediately below plate A there is formed a relatively narrow face or section F, 30 which inclines inwardly from its upper to its lower edge. Extending down from said section F is an outwardly-flaring skirt or rim G, the skirt extending outside of the cup-shaped member E and terminating at a point above 35 the lower end thereof.

Having thus described my invention, what I claim is—

The design for a bobbin-holder and thread-catcher, substantially as herein shown and 40 described.

In witness whereof I hereunto set my hand in the presence of two witnesses.

RUSSELL C. BLAKESLEE.
